F. SAYLES,
SHAVING ARTICLE.

APPLICATION FILED MAY 4, 1918.

Patented Jan. 21, 1919.

1,292,084.

THE MORRIS PETERS CO., PHOTO-LITHO., WASHINGTON, D. C.

UNITED STATES PATENT OFFICE.

FREDERICK SAYLES, OF CHICAGO, ILLINOIS.

SHAVING ARTICLE.

1,292,084.

Specification of Letters Patent.

Patented Jan. 21, 1919.

Application filed May 4, 1918. Serial No. 232,556.

To all whom it may concern:

Be it known that I, FREDERICK SAYLES, a citizen of the United States, residing at Chicago, in the county of Cook and State 5 of Illinois, have invented certain new and useful Improvements in Shaving Articles, of which the following is a specification.

This invention relates to improvements in shaving articles and one of the objects of 10 the same is to provide an improved article of this character, embodying a shaving brush and mug adapted to be detachably secured together so that the brush will be inclosed within and protected by the mug when not 15 in use. The brush is provided with a chamber in its handle for containing a supply of powdered soap and the said chamber is provided with a cover adapted to be adjusted with respect to the chamber, where- 20 by the powdered soap may be dispensed.

A further object is to provide an improved cover for the mug, adjustably mounted upon the brush handle and which cover serves as a drip cup when the brush 25 is in use, which will prevent any excess of lather or water taken up by the brush from flowing down upon the hand of the user, and will also serve the same purpose when the brush is inverted and stood upon a sup- 30 port.

To the attainment of these ends and the accomplishment of other new and useful objects as will appear, the invention consists 35 in the features of novelty in substantially the construction, combination and arrangement of the several parts, hereinafter more fully described and claimed and shown in the accompanying drawing, illustrating this invention, and in which;—

40 Figure 1 is a side elevation of an improved device of this character constructed in accordance with the principles of this invention.

Fig. 2 is a vertical sectional view as taken 45 on line 2—2, Fig. 1.

Fig. 3 is a view partly in elevation and partly in section, showing the brush inverted and the drip cup adjusted upon the handle.

Fig. 4 is a horizontal sectional view on 50 line 4—4, Fig. 2.

In this invention the brush is provided with a hollow handle 10, which may be of any desired shape and configuration, and is provided with an open end closed by a 55 suitable closure 11, removably secured in position in any suitable manner, such as by

means of screw threads. The wall of the handle is provided with an opening 13, with which an opening 14, in the closure 11, is adapted to be brought into register and 60 through which registering openings the powdered soap 15, within the handle 10, may be sifted into the mug or cup 16, for use. When desired to fill the handle, the cover 11 may be readily removed. 65

The other end of the handle is preferably cylindrical, as at 17, and the extremity of such portion of the handle is adapted to be closed, preferably by the body 18, of the brush 19, and which body preferably ex- 70 tends into the handle and is secured in any desired or suitable manner. The body 18 of the brush is preferably in the form of a ferrule which is flanged over the extremity of the handle, as at 20, and the periphery 75 of the flanged portion is shaped to form a bead or projection and which projection co- operates with a shoulder 22, on the handle, to hold the closure 23 of the mug 16 and the brush against separation. 80

The closure 23 may be provided with a circumferential flange 24, by means of which the closure may be secured in position on the mug, such as by being screwed thereto, or otherwise. 85

The closure 23 is provided with an opening therethrough, and through which opening the cylindrical portion 17, of the handle passes, so that the closure may be adjusted upon the handle between the shoulder 22, 90 and the stop 21, to prevent separation of the parts.

The opening in the closure 23 is of a size only slightly larger than the exterior diameter of the cylindrical portion 17, of the 95 handle, so that the closure and handle will be frictionally held in their adjusted positions with relation to each other.

It will therefore be manifest that, when not in use, the brush and closure may be 100 relatively adjusted so that when the closure is secured to the mug, as in Fig. 2, the brush will be housed in the mug and protected thereby. This will also result in a sanitary arrangement. 105

When it is desired to use the outfit, the closure 23 and the brush therewith may be detached from the mug 16, and the closure then adjusted upon the handle to the desired position, so that the closure will form a drip 110 cup, while the brush is in use, to prevent any excess of lather and water taken up by the

brush from flowing down upon the fingers of the operator.

Furthermore, the closure 23 serves as a drip cup when the brush is not in use, and is inverted and stood upon its end, as shown in Fig. 3.

Obviously the closure 23 may be made of any suitable size to fit the mug to which it is to be applied.

10 It is also manifest that many changes may be made in the details of construction and in the combination and arrangement of the several parts, within the scope of the claims, without departing from the spirit of this 15 invention.

What I claim as new is:

1. A shaving article embodying a shaving brush, a drip cup frictionally mounted upon the handle of the brush for adjustment longitudinally thereof, means for holding the 20 said drip cup and brush against separation, in combination with a receptacle, said drip cup when inverted forming a closure for the receptacle and adapted to be detachably secured to the receptacle.

2. A shaving article embodying a hollow brush handle constituting a powder receptacle having a discharge outlet adjacent one end, a closure for the outlet, a brush proper 25 detachably connected with the other end of the handle, a receptacle for lather, a closure

adapted to be detachably connected with the lather receptacle, the brush handle passing through the last recited closure whereby the two are relatively adjustable lengthwise of the brush handle, and spaced shoulders between which the last recited closure moves to hold the lather receptacle and the brush against separation, the last said closure also serving as a drip cup when the brush is inverted or in use.

3. A shaving article embodying a brush handle, a brush proper connected with the handle, a portion of the brush handle adjacent the brush being reduced to form a shoulder spaced from the brush, said reduced portion beyond the shoulder being of a uniform diameter throughout its length, a closure, forming a drip cup and freely slidable longitudinally upon the said portion of the brush handle and frictionally engaging said handle, a shoulder adjacent the brush and between which shoulders the said closure is adapted to be moved, whereby the shoulders will limit the movements of the closure, in combination with a receptacle for receiving the brush, and upon which receptacle the said closure is adapted to be fitted.

In testimony whereof I have signed my name to this specification, on this 2nd day of 60 May, A. D. 1918.

FREDERICK SAYLES.
